UNITED STATES PATENT OFFICE.

ALPHA H. METCALF, OF ATTLEBORO, MASSACHUSETTS, ASSIGNOR TO MARATHON COMPANY, SAMUEL M. EINSTEIN, PROPRIETOR, OF ATTLEBORO, MASSACHUSETTS.

KNITTING-NEEDLE.

1,268,752.

Specification of Letters Patent. Patented June 4, 1918.

Application filed February 18, 1918. Serial No. 216,869.

To all whom it may concern:

Be it known that I, ALPHA H. METCALF, a citizen of the United States, residing at Attleboro, in the county of Bristol and State 5 of Massachusetts, have invented a new and useful Improvement in Knitting-Needles, of which the following is a specification.

This invention relates to certain new and useful improvements in knitting needles, 10 and the primary object of the invention is to provide a set of knitting needles which are nested one within the other, so as to provide a simple and compact assemblage of the various needles, in a single unit.

15 A further object of the invention is to provide means for holding the needles assembled so as to prevent accidental separation of the individual needles, and to also provide a neat and attractive appearing article.

20 In the drawings—

Figure 1 is an elevation of the needles in their housed or nested state.

Fig. 2 is an enlarged detail view in longitudinal section, the lower parts of the needles being broken away.

Fig. 3 is a section on line 3—3 of Fig. 2. Fig. 4 is a fragmentary side elevation of the needles in the act of separating same.

In proceeding in accordance with the invention, an outer needle 1 is employed which constitutes a holder for the remaining two needles 2 and 3, the needles being hollow in formation, or tubular and provided with the usual point 4. The innermost needle 3 however could be made other than hollow if desired.

Each needle has a circular head though other forms of heads could obviously be employed, the heads 5, 6 and 7 being of decreasing diameter so as to present a somewhat pyramidal formation so as to not only present an attractive appearance but also more readily permit of the separation of the needles from their nested arrangement.

45 The needles are telescoped, one within the other, as depicted, in the drawings, and in order to prevent accidental separation of same, the outer or head end part of each needle 2 and 3 is formed with a series of 50 slits 8 extending up to the heads 6 and 7 thus forming a series of spring finger-like parts 9, which latter are bowed outwardly to form projections 10 which frictionally en-

gage the inner circumferences of the next adjacent outer needles. By reason of the resiliency of the spring parts 9, it will be apparent that, since those parts project outwardly, pressure will be required to a slight degree to force the needles into internest- 55 ing position, and the same will consequently be held in such positions, by the frictional contact between the parts 9 and the inner circumferential wall of the surrounding needle. 60

The spring parts or fingers 9 are disposed adjacent the heads of the needles, so as to 65 require less force in separating the needles, or withdrawing same, due to the fact that the parts 9 are close to the points at which the force is applied.

70 Preferably, three needles comprise a set, the outer needle acting as a housing for the remaining two needles. Obviously, however, but two needles, or more than three may be made to constitute a set.

75 From the foregoing it will be apparent that the needles are internested and appear as a unit, or as a single needle. This not only facilitates carrying of the needles, but prevents the same from being lost or separated, one with respect to the other or others. 80 In addition, less space is required to store the needles, and since the needles are tubular they are light in weight and easily manipulated.

Having thus described my invention, what 85 I claim as new and desire to secure by Letters Patent is—

1. A set of knitting needles composed of a hollow needle, and a second needle received on the interior of the hollow needle, said 90 needles being of substantially the same length and diameter and each having a handle and a point.

2. A set of knitting needles composed of a hollow needle, a second needle movably 95 received in the first needle, said second needle being formed with relatively short slits and the metal between the slits being bowed outwardly to form spring-like projections engageable with the inner circumferential 100 wall of the hollow needle so as to hold the needles against accidental separation.

3. A set of knitting needles composed of a series of hollow outer needles receivable one within the other and an inner needle 105 receivable in the inner one of the outer nee-

dles, all of the needles being of approximately the same diameter and length so as to each have a handle of similar length.

4. A set of knitting needles composed of
5 a hollow outer needle, a hollow inner needle receivable on the interior of the outer needle and having a head engaging the adjacent end of the outer needle, said inner needle having a series of relatively short spaced
10 slits extending to its head and having the

material between the slits bowed outwardly to form spring fingers to engage the inner circumferential wall of the outer needle.

In testimony whereof I have signed my name to this specification in the presence of 15 two subscribing witnesses.

ALPHA H. METCALF.
